DESIGN FOR A SAFE OR SIMILAR ARTICLE

Palmer Bescherer, York, Pa., assignor to York
Safe and Lock Company, York, Pa., a corporation of Delaware

Application December 23, 1939, Serial No. 89,106

Term of patent 14 years

To all whom it may concern:

Be it known that I, Palmer Bescherer, a citizen of the United States of America, residing at York, in the county of York and State of Pennsylvania, have invented a new, original, and ornamental Design for a Safe or Similar Article, of which the following is a specification, reference being had to the accompanying drawings, forming part thereof, wherein

Fig. 1 is a front elevation of the safe with the doors closed, showing my new design;

Fig. 2 is a front elevation of the safe with the doors open; and

Fig. 3 is a plan of the safe with the doors open.

I claim:

The ornamental design for a safe or similar article, as shown.

PALMER BESCHERER.
